UNITED STATES PATENT OFFICE.

VICTOR EDWARD LANE, OF BROOKLYN, NEW YORK.

SPRING-WHEEL.

1,052,350.

Specification of Letters Patent. Patented Feb. 4, 1913.

Application filed April 3, 1912. Serial No. 688,206.

To all whom it may concern:

Be it known that I, VICTOR E. LANE, a citizen of the United States, residing in Brooklyn, county of Kings, State of New York, have invented a new and Improved Spring-Wheel, of which the following is a full, clear, and exact description.

This invention relates to that type of resilient wheels which are commonly employed on pleasure and commercial vehicles, and among the objects aimed at in the present improvement, is to construct a wheel of this type which is neat in appearance, compact and practically dust-proof with respect to 15 movable parts.

Another object is to construct a wheel which has considerable freedom of movement and elasticity with respect to vertical movements, but which is substantially solid 20 with respect to transverse movements.

A still further object is to construct a wheel of this type in which the strains incident to flexibility, are all equally distributed among the several component parts of the 25 buffer or compression mechanism.

The foregoing and other objects of the invention are attained in a preferred embodiment, by means of the mechanism herein-after fully described and claimed and illustrated on the accompanying drawings, wherein the several parts are referred to by like reference characters in the several figures, and in which—

Figure 1 is a side elevation of a wheel 35 made in accordance with this invention, one of the side plates being partially broken away; and Fig. 2 is a vertical transverse section on the line 2—2 of Fig. 1 on a larger scale.

40 This wheel comprises essentially the following parts: a felly 10, to which may be connected any suitable or approved form of rim 11 and tire 12; a hub 13, and a body portion 14, shown in this case as comprising a pair of side plates 15, and a series of 45 spokes 16, rigidly connected to the side plates and the felly, whereby the felly, spokes and side plates constitute a practically rigid structure. The parts thus far 50 described are more or less conventional and may be variously constructed within the spirit of this invention.

The hub 13 is preferably constructed to 55 include a circular series of transverse cylindrical bosses 17, arranged preferably in the plane of the spokes and tire. The hub

also is shown as comprising a pair of spaced parallel flat flanges 18, extending outwardly radially of the wheel toward said bosses and against the outer faces of which the inner 60 edges 15^a are adapted to operate and whereby the wheel is prevented from sidewise or lateral distortion throughout its sphere of operation. Coöperating with said cylindrical bosses are a series of buffer or compression means of peculiar construction. This construction embodies a pair of cups 19, mounted in each of said bosses and movable toward and from each other therein. Between each pair of cups is a compression 70 spring 20, tending normally to separate said cups. The separation or outward movement of the cups is prevented or limited by co-operation with as many cones 21, carried by or upon the inner faces of the side plates 75 15. While the relative arrangement of each cup and its coöperating cone may be varied, the construction shown is one in which the cone extends into a concavity in the cup. When there is relative movement between 80 the main body of the wheel and the hub in a vertical plane, the cones 21, in gliding over the concave surfaces of the cups, may cause the cups of the several pairs to approach each other, putting the interposed 85 springs under compression, but which movement of the cups will be limited by their contact together, before any possibility of the separation of the cups from their respective cones may take place. All of the 90 compression means are preferably of the same construction and the arrangement is such that all strains tending to distort the wheel in a vertical plane, will be equally distributed among all of them, whereby the 95 resiliency of the wheel may be effected in a superior manner and yet provide that there shall be no lateral or sidewise distortion or weakness occasioned.

It is to be understood that the several 100 parts of this wheel may be variously constructed, as to materials or relative sizes and proportions, according to the exigencies or requirements of any particular demand, and I do not wish to be limited to the features 105 illustrated, except as may be required by the state of the art.

Having thus described my invention, I claim as new and desire to secure by Letters 110 Patent:

In a spring wheel, the combination of a hub having a pair of spaced parallel flat

flanges and a series of transverse bosses extending outwardly between and radially beyond said flanges, a wheel body, including a pair of side plates embracing said bosses and coöperating slidably with said flanges, and compression means comprising a series of pairs of cups mounted for transverse slidable movement in the respective hub bosses, a series of pairs of cones carried by the said side plates and coöperating each to

each with said cups, and a spring between each pair of cups and tending to force them apart in their coöperation with said cones.

In testimony whereof I have signed my name to this specification in the presence of 15 two subscribing witnesses.

VICTOR EDWARD LANE.
